Primary Examiner — Sheryl Lane*Assistant Examiner* — Samantha N Wood(74) *Attorney, Agent, or Firm* — Sterne, Kessler, Goldstein & Fox P.L.L.C.(57) **CLAIM**

The ornamental design for a guitar headstock, as shown and described.

DESCRIPTION

FIG. 1 is a top front perspective view of a guitar headstock showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom perspective view thereof.

The dashed broken lines in the figures show portions of the guitar headstock that form no part of the claimed design.

The dot-dash broken lines in the figures show boundaries that form no part of the claimed design.

The shade lines in the figures show contour and not surface ornamentation.

1 Claim, 6 Drawing Sheets(56)
